E. EKSERGIAN

CIGARETTE HOLDER

Filed April 22, 1921

INVENTOR

EDWARD EKSERGIAN

BY *John C. Conroy* ATTY.

UNITED STATES PATENT OFFICE.

EDWARD EKSERGIAN, OF ST. LOUIS, MISSOURI.

CIGARETTE HOLDER.

Application filed April 22, 1921. Serial No. 463,593.

To all whom it may concern:

Be it known that I, EDWARD EKSERGIAN, a citizen of the United States, residing at city of St. Louis, State of Missouri, have 5 invented a certain new and useful Improvement in Cigarette Holders, of which the following is a full, clear, and exact description, such as will enable others skilled in the art to which it appertains to make and 10 use the same, reference being had to the accompanying drawings, forming part of this specification.

My invention comprises a cigarette holder comprising a handle having a split portion 15 forming cigarette holding jaws and provided with a clamping ring.

The objects of my invention are to provide a device which eliminates the necessity of holding the cigarette in the fingers and 20 which permits the cigarette to be laid down on any surface without damaging the same and which forms an attractive and useful gift novelty.

In the accompanying drawings which illustrate a selected embodiment of my invention.

Figure 1 is an elevation of my device with a cigarette held therein.

Figure 2 is an elevation looking at right 30 angles to the direction from which Figure 1 is seen and showing the device at rest upon a table top or similar surface.

Figure 3 is a detail view of the clamping ring.

The handle 1 is preferably formed of 35 tubular material and is slotted inwardly at 2 for a substantial distance from one end. The portions of the handle on each side of the slot are bent outwardly and their terminations form semi-circular jaws 3 adapted to receive a cigarette and when pressed together to hold the same securely but without crushing it.

A ring 4 is slideable along handle 1 and 45 furnishes the clamping means. The material of the handle should possess sufficient springiness to separate when ring 4 is withdrawn from its clamping position. The jaws 3 are so formed that their edges contact when the semi-circular faces cooperate 50 to form a circle approximating the diameter of the average cigarette.

Ring 4 is provided with projections 5 adapted to support the ring and the adjacent portion of the handle from a surface upon which the holder is laid.

The split portions of the handle are narrowed and the ring is made oval in shape so that it will not be rotatable about the axis of the handle. Projections 5 are located on one of the narrow ends of the ring and this arrangement provides that the gripping faces of jaws 3 will always be at right angles to the projections 5 and accordingly parallel with the surface upon which the holder is laid.

I prefer to place the weight 6 in the un-split end of the holder which is the portion grasped by the fingers of the user. This adds solidity to the device and insures the 70 spacing of the cigarette end from a supporting surface when the holder is laid down.

In a design in which a clamping ring was located near the longitudinal center of the handle, the likelihood of the cigarette end 75 contacting with the supporting surface would be great enough to justify the addition of weight 6 for the purpose mentioned.

I contemplate the usual modifications of 80 the features described in the commercial development of my holder without departing from the scope of my invention as set forth in the following claims.

I claim:—

1. A cigarette holder comprising a tubular handle split longitudinally near one end with the terminals of its split portion bent to form opposed semi-circular jaws having gripping faces extending parallel 90 with the split and with the split portions narrowed in the direction of the split, a clamping ring slidably and non-rotatably mounted on the narrowed split portions of the handle and supporting projections extending radially from said ring.

2. In a cigarette holder, a handle one end of which comprises opposed longitudinal elements of springy material diverging from each other and terminating in jaws 100 adapted to receive a cigarette between them, a ring encircling said elements and slideable thereon and adapted to clamp their jaws when spaced a substantial distance therefrom, and projections on the exterior of 105 said ring whereby the jaws are raised from any surface upon which the holder may be laid, and means for maintaining a predetermined angular relation between said projections and the gripping faces of said jaws.

3. In a cigarette holder, a longitudinal handle weighted at one end and split for a

substantial distance from its opposite end with the split portions terminating in a pair of cigarette holding jaws and, behind said jaws, being of greater dimension in one direction through the handle than in the transverse direction, an elongated clamping ring encircling the split portion and slidable thereon, and exterior projections on said ring extending in a direction at right an-

gles to the gripping faces of the cigarette holding jaws whereby a cigarette held by the latter is raised from and held parallel with a surface upon which the holder is laid.

In testimony whereof I hereunto affix my signature this 16th day of April, 1921.

EDWARD EKSERGIAN.
